UNITED STATES PATENT OFFICE.

KARL KOLLER, OF BUDAPEST, HUNGARY.

ROTARY GRATE FOR GAS PRODUCERS.

Application filed April 19, 1921. Serial No. 462,705.

To all whom it may concern:

Be it known that I, KARL KOLLER, a subject of the King of Hungary, residing at Budapest, Hungary, have invented certain new and useful Improvements in Rotary Grates for Gas Producers, of which the following is a specification.

The invention has particular reference to a rotary grate, particularly adapted for use in gas producers utilizing brown coals and lignites, comprising several independently-rotatable sections, and means for rotating said sections at different speeds.

In gasifying lignites and brown coals with great content of ashes and producing much slag, grates heretofore devised and used do not stoke to the necessary extent the forming cap of slag, which necessitates knocking the cap occasionally by the use of breaking-rods, and this naturally disadvantageously affects the production of gas.

According to this invention, the rotary milling-grate, serving as the bottom of the gas-producer, comprises coaxially-arranged, independently-rotatable substantially conical sections rotatable in either direction, thus preventing the formation of a cap of slag, and avoiding the objection noted above.

The invention also resides in certain specific improvements in the grate, as will appear in the following description of the construction thereof.

The accompanying drawing discloses the preferred embodiment of the invention, in which—

Figure 1 is a central vertical sectional view of the device, and

Figure 2 is a top plan view thereof.

Referring, now, in detail, to the drawing:

A designates the slag-plate of the gas-producer. The slag-plate is substantially truncated cone-shaped, as shown, and is preferably provided, at its lower end, with an annular, circumferential, horizontal, basal flange b, resting upon anti-frictional ball-bearings b' in the annular groove of a track-ring b².

Secured to the flange b at its outer or free circumferential edge is a toothed ring Z², meshing with a screw S² on a rotatable shaft s rotatably driven from any suitable source of power.

Carried by the flange b, on top thereof,

may be an annular, upward and outward inclined shelf b³ having, at its top, a circumferential, downward-inclined rim b⁴.

The conoidal slag-plate A is provided, at its top, with an opening a, through which extend the supporting stems C and B' of the grate-sections.

The stem C may, if desired, be in two sections, as shown in the drawing,—a relatively long section and a short section, C', both hollow, and the latter, as well as the flaring upper portion b⁵ of the stem B' being provided with side openings d.

The stem B' flares outward toward the top and bottom thereof, as shown at b⁵; b⁶, respectively, the flaring portion b⁵ supporting the grate-section B, which, as shown, is a substantially truncated conoidal member, provided with transversely-extending longitudinally curved shearing blades b⁷ on its upper surface. The flaring portion b⁶ terminates, at its bottom, in a basal, annular, horizontal flange b⁸ having, on its perimeter worm-teeth Z¹ meshing with a worm S¹ rotatably driven from any suitable source of power.

The stem C is provided, at its bottom, with a correspondingly outward-flared portion c¹ terminating in a corresponding basal, annular, horizontal flange c² provided, on its perimeter, with worm-teeth Z² meshing with a worm S² driven from any suitable source of power.

Between the basal flanges b⁸ and c² and between the latter and a bed-plate X are disposed anti-friction ball bearings b⁹.

As shown, the stems B' and C are concentric and telescopically arranged, and have, as their axis of rotation, a vertical shaft or axle Y resting, at its bottom, in a depending, hollow stem x of the bed-plate X.

The shorter section c¹ of the stem C depends from and supports the conoidal grate-section c, which is of a dimension to extend over the top, central opening b in the grate B.

The grate c terminates, at its top, in an upward-projecting hollow nose c³ having side openings c⁴ and covered by a cap c⁵, which projects beyond the side wall of the nose, as shown. The grate c is provided with transversely-extending ribs b⁷ on its upper surface.

As shown, the grate sections B and c

are disposed in different horizontal planes, i. e., they are disposed in superposed relation, with the smaller grate-section *c* disposed above the larger grate *B*. The grates 5 are of different sizes.

The slag-plate *A* functions, as usual, to displace the slag outwardly.

The stem *B'* is provided, toward its top, with side openings *d*, which serve for the 10 supply of air, as do, also, the openings *a* beneath the grate-section *c* and the corresponding openings *c'* beneath the hood or cap *c'*.

The slag-plate *A* preferably has, on its 15 top surface, transversely extending ribs *A'*.

It will now be noted that, by the construction described, the grate-sections may be rotated in either direction at different speeds. The number of the grate-sections may be 20 varied, according to requirements, and, while I have shown two of such sections, more may be used, obviously, if required.

The relative speeds of the grate-sections

prevent the formation of slag-caps, as distinguished from the constructions known to me, in which the formation of slag has been promoted by the decrease of the revolving speed from the periphery to the center of the grate.

Having thus fully described my invention, 30 what I claim as new and desire to secure by Letters-Patent is:

A rotary grate for gas-producers, comprising a plurality of substantially conical, superposed, co-axial grate-sections independently rotatable in either direction, each of said grate-sections being provided on its upper surface with transversely-extending, longitudinally-curved shearing-blades. 35

In testimony whereof I have signed my 40 name to this specification in the presence of two subscribing witnesses.

KARL KOLLER.
